UNITED STATES PATENT OFFICE.

CHARLES W. HAMILTON, OF MILWAUKEE, WISCONSIN.

DESIGN FOR LACE PAPER.

50,301.

Specification for Design.

Patented Feb. 13, 1917.

Application filed November 9, 1916. Serial No. 130,485. Term of patent 14 years.

To all whom it may concern:

Be it known that I, CHARLES W. HAMILTON, a citizen of the United States, residing at Milwaukee, in the county of Milwaukee and State of Wisconsin, have invented a new, original, and ornamental Design for Lace Paper, of which the following is a specification, reference being had to the accompanying drawing, forming part thereof.

The figure is a plan view of a portion of lace paper illustrating my new design.

Copies of this patent may be obtained for five cents each, by addressing the "Commissioner of Patents, Washington, D. C."

I claim:

The ornamental design for lace paper, as shown.

In testimony that I claim the foregoing I have hereunto set my hand at Milwaukee, in the county of Milwaukee and State of Wisconsin, in the presence of two witnesses.

CHARLES W. HAMILTON.
